COMBINED BASKETBALL GOAL AND RECREATIONAL EQUIPMENT TRAILER OR THE LIKE

Harold W. Haubert, Mifflintown, Pa., assignor, by mesne assignments, to Zenith Laboratories, Inc., Englewood, N.J., a corporation of New Jersey

Filed Nov. 15, 1968, Ser. No. 14,485

Term of patent 14 years

Int. Cl. D12—10

U.S. Cl. D14—3

Fig. 2

Fig. 1

Fig.4

FIG. 1 is an end perspective view of a recreational equipment trailer having all of the access openings closed and with the basketball backstop assembly in folded position;

FIG. 2 is a perspective view as seen from the opposite end of the recreational equipment trailer shown in FIG. 1;

FIG. 3 is an end perspective view of the recreational equipment trailer shown in FIG. 1 having all of the access openings open and with the basketball backstop assembly in its erected position; and

FIG. 4 is a perspective view as seen from the opposite end of the recreational equipment trailer shown in FIG. 3.

I claim:

The ornamental design for a combined basketball goal and recreational equipment trailer or the like, substantially as shown.
